UNITED STATES PATENT OFFICE.

OLIVER NORDEN, OF CHICAGO, ILLINOIS, ASSIGNOR TO THE WM. MEYER COMPANY,
OF CHICAGO, ILLINOIS, A CORPORATION OF ILLINOIS.

TAKE-UP REEL.

Application filed February 18, 1924. Serial No. 693,434.

To all whom it may concern:

Be it known that I, OLIVER NORDEN, a citizen of the United States, residing at Chicago, in the county of Cook and State of Illinois, have invented a certain new and useful Improvement in Take-Up Reels, of which the following is a full, clear, concise, and exact description, reference being had to the accompanying drawings, forming a part of this specification.

This invention relates to tension reels and winding devices and more particularly to reels of the spring take-up type.

The invention pertains especially to take-up reels for use in high tension X-ray tube circuits and the like, and its objects are to improve the electro-static characteristics of such devices, particularly to the end of minimizing corona losses and to provide improved means for mounting the reel upon any desired support, an improved mounting for mounting said mounting means on the reel and a generally improved and simplified reel construction that may be economically produced.

To acquaint those skilled in the art with the manner of constructing and using the invention I will now describe in connection with the accompanying drawings a specific embodiment of the invention.

In the drawings:

Figure 1 is a side elevational view of a reel embodying the invention;

Fig. 2 is a vertical section on line 2—2 of Fig. 3; and

Fig. 3 is a vertical section on line 3—3 of Fig. 1.

The reel shown comprises an axle 6, side members 7 and 8 which are preferably of relatively thin metal stock and of circular formation, and a circular metallic ring 9 upon and from which and between side members 7 and 8 conductor 10 is wound and unwound. Within ring 9 and between side members 7 and 8 is a flat spiral spring 12 attached at one end by a pin 13 to axle 6 and at its opposite end to one of a plurality of screws 15 which extend through and bind side members 7 and 8 together with ring 9 between them. Side members 7 and 8 and ring 9 are rotatable as a unit about axle 6 and spring 12 is tensioned by the relative rotation in unwinding the conductor 10 and acts to tension the conductor and maintain it taut and to rewind it. Side members 7

and 8 are dished outwardly at 16 forming offset margins 17 which are preferably spread slightly as shown. The dishing or turning out at 16 is blunt, preferably rounded to eliminate sharp corners and reduce 60 corona loss.

The axle 6 has an enlargement 18 and is reduced at 19 to receive an outer side member or shield 20 spaced from side member 8 by enlargement 18 and provided with a central opening which fits over the reduced end 19. Side member 20 which is formed of sheet metal, preferably aluminum and which is preferably of circular formation, is clamped between head 18 and washer 21 by 70 a screw 22 threaded into one end of a tapped bore through the axle. Mounted upon the opposite end of axle is a spacing member 24 reduced at 25 to fit in the central opening in a similar side member or shield 23, 75 which is clamped between the shoulder on the spacing member 24 and a washer 26 by a screw 27 threaded into tapped axle 6.

The outer side members 20 and 23 are dished at 30 to conform to side members 7 80 and 8 and the margins of said side members 20 and 23 are turned in laterally at 32 and extend circumferentially about the reel with a space 35 between them annularly about the reel. The inner edges of the inturned margins 32 terminate in blunt, preferably rounded beads 34 and the corners 33 are blunt, preferably rounded as shown. The dishing at 30 is also blunt, preferably of double rounded formation to eliminate sharp 90 corners.

The side members or shields 20 and 23 are in circuit with the conductor on the reel and they eliminate the corona losses which, where high tension current is involved, 95 would otherwise occur at the sharp annular edges of side members 7 and 8. The rounding or blunt formation of corners 33 and the rounded or blunt formation of edges 34 reduces the corona losses or potential gradient from the edges and corners of the outer side members or shields to a minimum. 100

The inturned margins 32 shield the interior of the reel and support a mounting post mounted in the annular opening 35 between the edges of the inturned margins 32. The mounting post comprises a threaded stem 36 which projects out through annular opening 35 and has at its inner end a head 110 37 which may be formed integral with the

stem or riveted, welded or otherwise secured thereto. Head or enlargement 37 is preferably curved circumferentially of the reel to conform to the inner surfaces of inturned margins 32. At its base stem 36 may be enlarged at 38 and the sides of enlargement 38 flattened to cooperate with and space the inner beaded edges 34. Stem 36 projects out through opening 35 and threaded upon its projecting end is a nut 39 which upon being drawn or threaded up into cooperation with the outer surfaces of inturned margins 32 binds the mounting post securely in place upon the lateral flanges of side members 20 and 23. A screw 40 threaded into the opposite end of nut 39 permits mounting the reel as desired either supported or suspended upon the X-ray table or other support.

20 In use high tension current is supplied to the reel as by connecting the conductor from a source of alternating current to the mounting post 36 which thereby performs the dual function of mounting the reel and providing for electrical connection therewith. The mounting post parts being of conducting material and all in good electrical contact the current travels through the corona shields 20 and 23 to axle 6 with which the shields are also in good electrical contact and through the axle, inner reel frame and spring to the inner end of conductor 10 which is electrically and mechanically connected with ring 9 as by soldering it in an opening in said ring as shown at 42. The conductor shown is insulated, in which case the insulation is removed at the point of connection with ring 9. While the employment of an insulated conductor maintains the resistance of the conductor substantially constant in its various wound and unwound conditions as more fully explained in my co-pending application, Serial No. 359,685 filed February 18, 1920, the conductor may be insulated or uninsulated in so far as the present invention is concerned.

50 The free end of the conductor extends out through the annular opening 35 and is connected as desired to the tube or other desired circuit. As the distance from the reel to the tube or other point of connection is increased, the conductor 10 unwinds from the reel and this tensions spring 12 so that as the tube or other point of connection is moved nearer the reel the slack in conductor 10 is automatically taken up by spring 12 and the conductor is maintained taut at all times and rewound by the spring upon being released.

60 Shields 20 and 23 perform the dual function of forming a mounting for the post 36 and eliminating corona losses from the sharp edges of side members 7 and 8 and the blunt corners 33 and blunt edges 34 minimize the corona discharge from the shields.

The width of opening 35 being less than the distance between the outturned ends of side members 7 and 8 and centrally disposed relative thereto, said opening forms a guide for guiding the conductor from and back into proper position upon the reel. The particular point of connecting the supply circuit to the reel may be varied. For example, instead of making the connection to post 36 connection may be made directly to the axle under one of the shield mounting screws. It is also to be understood that the invention is not limited to the details of the particular inner reel structure shown and described.

80 The sheet metal of the shields or side members 20 and 23 is relatively light, and lends itself admirably to the formation of the lateral mounting flanges for the mounting post and to the formation of the corona reducing beads 34 and blunt corners 33. The mounting flanges of these side members 20 and 23 are preferably turned in and extend annularly about the side members as described, but it is to be understood that 90 they may be turned outwardly instead of inwardly to support the means for mounting the reel and they need not extend annularly about the entire periphery of the side members, but may be in the form of 95 marginal lugs turned laterally in either direction with the fold or corner about which they are turned, formed bluntly, preferably rounded and the edges of the side members and the edges of said lugs formed bluntly 100 or terminating in blunt, preferably rounded, beads to reduce corona losses.

I claim:

1. In combination, an axle, a reel rotatable thereon, an enlargement which serves 105 as a spacer at one end of the axle, a side member mounted adjacent the outer face of the enlargement, a spacing member on the other end of the axle, a side member mounted on the axle with said spacing member between it and the reel, said side members having inturned margins terminating in blunt beads spaced apart and defining an annular opening about the reel and the corners between the sides of said members 115 and the inturned margins being rounded, a conductor attached to the reel and adapted to be wound upon and unwound from said reel and to extend through said annular opening, and a mounting post mounted in 120 said opening, said post having an enlargement for cooperation with the interior of said inturned margins and a nut threadable upon said post into cooperation with the exterior of said margins.

125 2. In combination, an axle, a reel rotatable thereon, an enlargement which serves as a spacer at one end of the axle, a side member mounted adjacent the outer face of the enlargement, a spacing member on the other 130

end of the axle, a side member mounted on the axle with said spacing member between it and the reel, said side members having inturned margins terminating in blunt beads spaced apart and defining an annular opening about the reel and the corners between the sides of said members and the inturned margins being rounded, a conductor attached to the reel and adapted to be wound upon and unwound from said reel and to extend through said annular opening, and a mounting post secured to the two shields and extending out between the edges thereof.

In witness whereof, I hereunto subscribe my name this 14th day of February, 1924.

OLIVER NORDEN.
